US00D820956S

(12) **United States Design Patent** (10) **Patent No.:** **US D820,956 S**
Ito et al. (45) **Date of Patent:** **** Jun. 19, 2018**

(54) **REGULATOR**

(71) Applicant: **SMC CORPORATION**, Tokyo (JP)

(72) Inventors: **Shinichi Ito**, Toride (JP); **Michihiro Hanada**, Tsukubamirai (JP)

(73) Assignee: **SMC CORPORATION**, Tokyo (JP)

(**) Term: **15 Years**

(21) Appl. No.: **29/599,148**

(22) Filed: **Mar. 31, 2017**

(30) **Foreign Application Priority Data**

Oct. 11, 2016 (JP) 2016-021993

(51) **LOC (11) Cl.** **23-01**

(52) **U.S. Cl.**
